UNITED STATES PATENT OFFICE.

FRANK C. FIX, OF CINCINNATI, OHIO, ASSIGNOR TO ARMSTRONG CORK COMPANY, OF PITTSBURGH, PENNSYLVANIA, A CORPORATION OF PENNSYLVANIA.

INSOLE-TRIMMING MACHINE.

1,367,870.

Specification of Letters Patent.

Patented Feb. 8, 1921.

Application filed April 1, 1918. Serial No. 225,872.

To all whom it may concern:

Be it known that I, FRANK C. FIX, a citizen of the United States, residing in Cincinnati, Hamilton county, Ohio, have invented a new and useful Improvement in Insole-Trimming Machines, of which the following is a full, clear, and exact description, reference being had to the accompanying drawings, forming part of this specification, in which—

Figure 1 is a side elevation partially in section of one form of my improved machine.

Fig. 2 is a diagrammatic sectional view on the line II—II illustrating the gearing.

Fig. 3 is a front view of the machine.

Fig. 4 is a plan view of a reinforced insole, after it has passed through the machine, and

Fig. 5 is a detail sectional view on the line V—V of Fig. 4.

This invention relates to an improvement in trimming machines for reinforced insoles, and is designed to provide an inexpensive and efficient machine which will secure the reinforce to the insole, so that after the insole has been passed through the machine, the surplus stock trimmed from the insole will adhere thereto. In machines of this character the clippings or trimmed off portion would very frequently hang freely from the insole during its passage from the machine, and sometimes would be caught in the gearing and jam the machine.

By the use of an improvement, such as shown and described, the trimmed portion will adhere to the insole, and is removed after the insole has passed through the machine.

The precise nature of my invention will be best understood by reference to the accompanying drawings, which will now be described, it being premised, however, that various changes may be made in the details of construction and general arrangement of the parts, without departing from the spirit and scope of my invention, as defined in the appended claims.

In the drawings I have shown my improvement in connection with an insole reinforcing and trimming machine, such as shown and described in my co-pending application Serial No. 193,728, and in which the reference character 2 designates the frame of the machine. The frame of the machine is provided with standards 3 having bearings for the main shaft 4 and a countershaft

5. The main shaft is provided with a fast and loose pulley, as well as a pinion 6, which

meshes with a spur gear 7 on the shaft 5. The main shaft 4 is connected to a spindle 8, by means of bevel gears 9, which spindle co-acts with the feed wheel 10 and a rotary table 11 for forming the lip on an insole. The feed wheel 10 is connected to a horizontal spindle 12, which is positively driven through the medium of the gears 13 from the shaft 5, and connected to the spindle 12 65 is a bevel gear 14, which is arranged to rotate the table 11 through the medium of the gearing 15.

Adjustably connected to the frame of the machine is a knife bracket 16 in which is 70 adjustably mounted a trimming knife 17, which is arranged to trim the reinforcing canvas, or duck between the lip and the edge of the insole. Mounted for reciprocation in a guide in a bracket 18 secured to the machine, is a stem 19 of a hammer 20. This hammer 20 is reciprocated by means of a crank 21 on a shaft 22. The shaft 22 is arranged to be driven by the gears 23 from the main gear wheel 7. 80

The insole 24, such as shown in Fig. 4 of the drawing, is provided with a reinforcing piece 25 of duck or canvas, the underside of which is coated with an adhesive, so that the duck is firmly secured around 85 the lip and to the body of the insole by the adhesive. The insole, together with the reinforcing, is passed through the machine, the feed wheel 10 and the spindle 8 forcing the reinforce into the corners at the junctions of the lip and the insole, and while the insole is being passed through the machine the surplus stock of the reinforce is trimmed between the lip and the edge of the insole. The hammer 20 is reciprocated 90 very rapidly and pounds that portion of the reinforce between the lip and the insole firmly on to the insole, so that when the insole is trimmed, when passing a knife 17, the surplus stock will adhere to the body 95 of the insole and thereby prevent the same from being dragged into the gearing. 100

The advantages of my invention result from the provision of means for hammering the reinforcing material firmly into contact 105 with the insole before passing to the trimming knife to cause the clippings or trimmed material to firmly adhere to the insole.

I claim:

1. An insole reinforce machine having a rotary table, means for rotating the table,

a rotary feed wheel arranged to press the reinforce against the outside of the lip and against the insole, means for rotating the feed wheel, a second forming wheel arranged to press the reinforce against the inside of the lip and which co-acts with the feed wheel to finish the rib for the welt, means for rotating said wheel, and a reciprocating hammer for pressing the reinforce into contact with the edge of the insole; substantially as described.

2. An insole reinforce machine having a rotary table, means for rotating the table, a rotary feed wheel arranged to press the reinforce against the outside of the lip and against the insole, means for rotating the feed wheel, a second forming wheel arranged to rotate about an axis at right angles to the axis of the feed wheel, said second forming wheel being arranged to press the reinforce against the inside of the lip and which co-acts with the feed wheel to finish the rib for the welt, means for rotating said second wheel, and a reciprocating hammer for pressing the reinforce into contact with the edge of the insole; substantially as described.

3. An insole reinforce trimming machine having a rotary table, means for rotating the table, a rotary feed wheel arranged to press the reinforce against the outside of the lip and against the insole, means for rotating the feed wheel, a second forming wheel arranged to press the reinforce against the inside of the lip and which co-acts with the feed wheel to finish the rib for the welt, means for rotating said wheel, a second device for pressing the reinforce into contact with the edge of the insole, and a trimming knife for trimming the excess reinforcing material behind the feed wheel; substantially as described.

4. An insole reinforce machine having a rotary table, means for rotating the table, a rotary feed wheel arranged to press the reinforce against the outside of the lip and against the insole, means for rotating the feed wheel, a second forming wheel arranged to rotate about an axis at right angles to the axis of the feed wheel, said second forming wheel being arranged to press the reinforce against the inside of the lip and which co-acts with the feed wheel to finish the rib for the welt, means for rotating said second wheel, a reciprocating hammer for pressing the reinforce into contact with the edge of the insole, and a trimming knife behind the feed wheel and the hammer; substantially as described.

5. In an insole reinforcing machine, means for pressing the reinforcing material into engagement with the lip, supplemental means for pressing said material directly into engagement with the insole between the lip and the edge thereof, and means for cut-

ting the reinforcing material intermediate the lip and the edge of the insole and within the area acted upon by said supplemental means in such manner that both cut edges of said material remain adhered to the insole, substantially as described.

6. In an insole reinforcing machine, means for pressing the reinforcing material into engagement with the lip, reciprocating means for pressing said material directly into engagement with the insole between the lip and the edge thereof, and means for cutting the reinforcing material intermediate the lip and the edge of the insole in such manner that the cut edges of said material remain adhered to the insole, substantially as described.

7. In an insole reinforcing machine, means effective on opposite sides of the insole lip for pressing the reinforcing material into engagement therewith, supplemental means for pressing said material directly into engagement with the portion of the insole between the lip and the edge of the insole, and means for cutting the reinforcing material within the area where it has been subjected to the action of said supplemental means, in such manner that both cut edges of said material remain adhered to the insole, substantially as described.

8. In an insole reinforcing machine, means for pressing the reinforcing material into engagement with the lip of the insole, means for cutting the reinforcing material between the lip and the edge of the insole, and means for pressing said material into engagement with the insole outside of the line of cut for holding the surplus material to the insole, substantially as described.

9. In an insole reinforcing machine, means for pressing the reinforcing material into engagement with the lip of the insole, means for cutting the reinforcing material between the lip and the edge of the insole, and means for pressing said material into engagement with the insole outside of the line of cut for holding the surplus material to the insole, said last named means being effective in advance of the action of the cutting means, substantially as described.

10. In an insole reinforcing machine, means for pressing the reinforcing material into engagement with the lip of the insole, means for cutting the reinforcing material between the lip and the edge of the insole, and means for pressing said material into engagement with the insole outside of the line of cut for holding the surplus material to the insole, said last named means being effective in advance of the action of the cutting means and on opposite sides of the line of cut, substantially as described.

11. In an insole reinforcing machine, an insole support, a feed wheel for pressing the reinforcing material into engagement

with the outside of the lip of the insole, and a reciprocating hammer coöperating with said feed wheel for forcing the material into engagement with the feather of the insole, substantially as described.

12. In an insole reinforcing machine, an insole support, a feed wheel for pressing the reinforcing material into engagement with the outside of the lip of the insole, and a

reciprocating hammer effective at one side 10 of the feed wheel and coöperating therewith for forcing said material into engagement with the feather of the insole, substantially as described.

In testimony whereof, I have hereunto set 15 my hand.

FRANK C. FIX.
